CLAIM

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with animated graphical user interface showing a first image in the sequence showing my new design, according to a second embodiment;

FIG. 2 is a second image thereof;

FIG. 3 is a front view of a display screen or portion thereof with animated graphical user interface showing a first image in the sequence showing my new design, according to a second embodiment;

FIG. 4 is a second image thereof;

FIG. 5 is a top view of the portable terminal;

FIG. 6 is the bottom view thereof;

FIG. 7 is the rear view thereof;

FIG. 8 is the left side view thereof; and,

FIG. 9 is the right side view thereof.

The broken lines around FIGS. 1-9 show a display screen thereof and form no part of the claimed design.

The appearance of the animated design sequentially transitions between the images shown in FIGS. 1-2 and 3-4, respectively. The process or period in which one image transitions to another forms no part of the claimed design.
